UNITED STATES PATENT OFFICE.

JEPPE JEPPESEN, OF PROVO CITY, UTAH TERRITORY.

WOOD-PLANING MACHINE.

SPECIFICATION forming part of Letters Patent No. 240,724, dated April 26, 1881.

Application filed September 28, 1880. (Model.)

To all whom it may concern:

Be it known that I, JEPPE JEPPESEN, of Provo City, in the county of Utah and Territory of Utah, have invented a new and useful Improvement in Wood-Planing Machines, of which the following is a specification.

My improved machine is intended for dressing both sides of boards at once, for dressing the edges at any angle desired, for tonguing and grooving, cutting moldings, and other varieties of work in wood.

I make use of two endless chains of links, fitted with cutters, combined with an adjustable bed, above and below which the chains are fitted to move in adjustable guides. I also use a feed-bed and feeding device, combined with circular saws, for carrying the material to the cutters and squaring the ends at the same time. The links of the chains are of peculiar construction, each being a plane having cutters adapted for doing the work required, according to the direction and manner of feed.

In the following description the construction and operation are described in detail with reference to the accompanying drawings, and the invention set forth in the claims.

In the drawings, Figure 1 is a front elevation of the machine with the frame partially broken open. Fig. 2 is a sectional plan view 30 of the same on line xx of Fig. 1. Fig. 3 is a vertical transverse section on line yy of Fig. 1. Fig. 4 is a face view of one of the planers. Fig. 5 is an end view of the same. Fig. 6 is a side view of one planer with the cap removed. Fig. 7 is a view representing the planers in position for tonguing and grooving.

Similar letters of reference indicate corresponding parts.

The frame of the machine consists of end standards, A A A A, tied by longitudinal rails a at top and bottom. Between the two standards A, at the front of the machine, is fixed a horizontal feed-bed, B, that extends the full length of the machine. The two standards A at each end of the machine are formed with vertical grooves in their adjacent faces to receive slide-blocks b . The blocks b at one end are connected with those at the other end by the guide-bars c of the endless chains. There

being an upper and lower chain, there are two blocks, b , above bed B, and two below the bed at each end of the machine. The construction is similar in both the upper and lower sections, and the following description is of the lower section: There is a guide-bar, c , at each side 50 of the chain. These are formed on their upper side with inwardly-projecting flanges c' , that sustain and guide the upper portion of the endless belt that is next to bed B, and at the lower portion of bars c there are fitted friction-rollers 55 d , upon which the lower portion of the chain runs, as shown most clearly in Fig. 3.

Upon the bars c at the ends of the machine are adjustable boxes for cross-shafts e , that carry gear-wheels e' , by which the chain is 60 driven. The chain consists of the planes C, jointed at their ends, described in detail hereinafter, which are formed with teeth on their inner surface for engagement with the wheels e' .

At the inner side of standard A are hung 70 levers f , extending to and connected with an arm, f' , from a head or block, g , that is fitted to slide in a vertical groove formed in the front rail, a . The block g is fitted for movement by means of an adjusting-screw, g' , secured in rail 75 a and engaging with nuts in the block, as shown in Fig. 1. There are two levers, f , at each end of the machine, connected separately by links h with the slides b , so that by the movement of block g the slides b , guide-bars c , and chain 80 are simultaneously moved to or from the bed B. The arrangement of parts for guiding and adjusting the upper chain is the same, except that the position is reversed. The chains are simultaneously driven by a belt from a pulley 85 on a driving-shaft, k^2 , to a pulley on upper shaft, e , and a belt from a counter-shaft, k' , to one of the lower shafts, e . Gearing may be substituted for the belts, if desired.

The devices for feeding the material forward 90 upon the bed B are constructed and operated as follows:

At the front of the machine, in bearings on standards A, is fitted a shaft, k , driven by bevel-gearing from a counter-shaft, k' , and carrying 95 bevel-pinions ll , that give motion to two short vertical shafts, m . The shafts m are fitted in suitable bearing-blocks, m' , at the ends of bed

B, and carry the feeding devices, which extend over bed B from front to back. These feeding devices may consist of endless chains *n*, having spiked links and fitted on grooved pulleys *o o*, the front pulleys being on the shafts *m* and those at the rear on studs fitted to arms that extend back from the blocks *m'*; or, in place of the chains, there may be a series of spiked wheels, *p*, (shown in Fig. 2,) that are upon short vertical arbors and driven by a train of gearing from shaft *m*. In connection with the feeding devices there are guides *p'*, for the material, fitted on bed B. The spikes of the feeding chains or wheels project from slots in guides *p'*, and at one end of the machine the bearing-block *m'* and guide *p'* are fitted adjustably on bed B, so that the space between them and the guide at the opposite end of the machine can be varied as required. To permit such adjustment the bevel-pinion *l* at that end is connected to shaft *k* by a feather and groove, so that it may slide, and an arm, *l'*, from block *m'*, extends into a groove in the hub of the pinion, whereby it is moved with the shaft *m* and kept in gear.

Upon the front of the bearing-blocks *m'* there are fitted brackets *q q*, on which short horizontal arbors *q' q'* are sustained in suitable bearings. On these arbors there are circular saws *r*, placed to cut in line with the guides *p'*. The arbors *q'* are driven from shaft *k* by belts and pulleys, as shown in Figs. 1 and 3.

Upon the guide-bars *c*, above bed B, there are hung levers *s*, which extend inward and are fitted at their inner ends with friction-rollers *s'*, that will bear upon the material on bed A, to hold the same in place. The outer ends of levers *s* are held up with the requisite force by weights *t*, that are on the end of bands which pass over pulleys *t'* to the ends of levers *s*.

The frames C, forming the links of the endless chains, are shown separately in Figs. 4, 5, and 6. These consist of a stock, *v*, having side flanges, *v'*, at the base, which flanges are grooved to take upon the edges of the flange *c'* of guides *c*. The face 1 of the plane is fitted with a cutter for planing the surface of boards. The side face, 2, is fitted with a cutter for use in dressing the edge of a board, and in connection with a cutter on the face 3 for rabbeting. The face 3 is on a shoulder of the plane, which shoulder can be provided with suitable cutters for tonguing and grooving. At the opposite side the plane is provided with a cap, *w*, held in place by a screw, so that it can be removed to give access to the cutters. This cap is fitted with the molding-cutter, and is shaped as required by the shape of the cutter. One cap is to be replaced by another, according to the shape of molding desired. These planes are connected together at their end by hinge-joints, to form the endless chain.

The operation of the machine is as follows:

To plane planks or boards the lower chain will be adjusted so that the cutters of the planes project above the surface of bed B through the opening, and the upper chain will be adjusted to or from bed B, according to the thickness of the boards. The planks or boards are then placed on the front of table B and pushed against the saws *r*, which square the ends, and the boards are then caught by the feeders *n* and carried between the planes. The rollers *s'* catch the planed boards and prevent them from rising.

To tongue and groove, the planes will be brought together, as shown in Fig. 7, so that a board may be received edgewise between the shoulders 3. A suitable bed, *w'*, will be placed above bed B, on which the boards will be placed edgewise, (see Fig. 7,) and a reciprocating feed-slide, *w*², used for carrying the boards forward to the planes. The forward board drops in front of the slide *w*² and is carried in to the planes. The adjusting-screws *g'* will then be slackened to allow the planes to work freely until the tongue and groove are made, when the planes will be separated to allow the finished board to drop out and another to be carried in.

In tonguing and grooving, the feed-slide *w*² retains the board in position until the planes have completed their work. The feed-slide is moved by hand to push the boards in and draw them out, and suitable levers are employed to relieve the chains from the completed board.

In rabbeting and forming moldings the operation is the same, except that for moldings the material is fed at the back of the machine.

Having thus described my invention, I claim as new, and desire to secure by Letters Patent—

1. In planing-machines, the combination of traveling endless chains composed of two parallel endless chains of planes jointed together, a feed-bed, and feeding-devices for carrying the material between the planes, substantially as shown and described.

2. In planing-machines, the combination of endless chains of planes C, provided with teeth or racks, adjustable guides *cc*, provided with flanges *c'*, and rollers *d*, cross-shafts *e*, and gear-wheels *e'*, substantially as and for the purposes set forth.

3. In planing-machines, the combination of traveling chains of planes C, provided with racks, guides *c*, shafts *e*, wheels *e'*, slides *b*, and grooved standards A, substantially as shown and described.

4. In planing-machines, the guides *p'*, feeding-chains *p*, pulleys *o o*, and feed-shaft *k*, connected by gears with said pulleys, combined with bed B, and endless chains of planes C, substantially as shown and described.

5. In planing-machines, the combination, with bed B, of the adjustable block *m'*, adjust-

able guide p' , feed-operating shaft m , and adjustable pinion l , substantially as and for the purposes set forth.

6. In planing-machines, the combination, with adjustable slides b , carrying the endless chains of planes, of the levers f , links h , slide-blocks g , having arms f' , and adjusting-screws

g' , substantially as and for the purposes set forth.

JEPPE JEPPESEN.
